ROLLER STRUCTURE FOR LIFT TRUCK CARRIAGES

Joseph A. Frischmann, Cleveland, Ohio, assignor
to Towmotor Corporation, Cleveland, Ohio, a
corporation of Ohio

Application March 31, 1951, Serial No. 218,655

6 Claims. (Cl. 187—85)

1

This invention relates to lift trucks of the type that embody a load-carrying carriage for vertical reciprocation on a mast of channel construction, and, more particularly, to guide roller arrangements for reducing the friction and improving the operational characteristics as the carriage travels along the mast.

In the operation of lift trucks, it is often necessary to lift loads of appreciable weight, and the placing of the loads on the carriage is sometimes eccentric to a considerable degree. Such eccentric loading places a great burden on the guide mechanism which holds the carriage as it travels along the mast. Failures in the guide mechanism have occurred due to lack of strength which results from a conventional arrangement of rollers and pintles for attaching the rollers to the carriage. High stresses on roller structures often cause the roller to slide, thereby producing a flat side on the roller and rendering the structure inoperable as an antifriction bearing means. Sliding of the roller causes scoring and seizing of the slide mechanism which is deleterious to the operation of the machine.

It is an object of this invention to provide a roller structure which is capable of carrying high loads without binding or distortion and is reasonably free from maintenance requirements.

Another object of this invention is to provide a roller structure for carrying the carriage along the mast which has a support member for holding the pin on which the roller rotates at the outer end for preventing bending which results when the pin is in cantilever relationship with the carriage.

A still further object of this invention is to provide a slide associated with the pin and roller structure for engagement with the channel to prevent movement of the carriage in a lateral direction as it moves along the mast.

Other objects and advantages, more or less ancillary to the foregoing, and the manner in which all the various objects are realized will appear in the following description, which, considered in connection with the accompanying drawings, sets forth the preferred embodiment of the invention.

In the drawings:

Fig. 1 is a side elevational view of the carriage and mast structure mounted on the conventional lift truck;

Fig. 2 is a detail of the roller structure with parts cut away to show details of construction;

Fig. 3 is an end view of the roller mounting; and

2

Fig. 4 is a side view of the roller mounting as it is associated with the channel members of the mast.

Referring first to Fig. 1, the numeral 10 designates a lift truck vehicle having a vertical mast 12 attached to the forward end thereof. The mast 12 is formed by two pairs of channel members opening toward each other, channel 14 being slidable inside of channel 16. A carriage 18 is mounted on the mast for vertical reciprocation and carries a fork 20 on which the load is deposited during operation. A cylinder and chain assembly 22 having a controllable hydraulic fluid supply under pressure supplies the necessary lifting force for raising the carriage 18 when the load is on the fork 20.

At each side of the carriage 18, a pair of rollers 24 is attached for travel in a vertical path internally of channel 14. The rollers 24 are spaced apart vertically to overcome the moment introduced by the load being carried on the forks 20. The structure provided for rotatably mounting the roller 24 on the carriage includes a yoke 26 which is affixed to the carriage 18. The yoke 26 has an opening formed therein in alignment with an opening in the carriage 18 which receives a pin 28. A roller bearing 30 is located intermediate the roller 24 and the pin 28 for carrying the roller 24 with a minimum of friction.

30 A pair of thrust washers 32 are located at each side of the roller 24 for positioning the roller relative to the carriage 18 and the yoke 26 and for holding the roller 24 out of sliding contact with the yoke and carriage. A flat elongated head 34 is formed on the end of the pin 28, the plane of the surface on the head 34 being normal to the centerline of the pin 28. The head 34 is in sliding engagement with the inner surface of the web of the channel 14 when the load on the carriage causes the carriage to shift laterally.

35 Adjustment of the height of the head 34 relative to the carriage 18 is provided by a plurality of shims 36 located between the head 34 and the yoke 26. By introducing the proper number of shims, lateral movement of the carriage may be reduced to a minimum and the necessary freedom for sliding may be retained.

40 A drilled passage 38 in the pin 28 communicates with the bearing 30 and with the end of the pin 28 opposite to head 34 wherein a greasing fitting 40 is affixed. Grease, introduced into fitting 40 by a conventional grease gun, will reach the bearing and thereby lubricate the roller as it travels along the channel 14.

55 A pair of ridges 42, parallel to the longitudinal

axis of the head 34, restrains the pin 28 from rotative movement when the roller turns thereon. It may be noted that no nut or keeper is required for the pin 28 since the assembly cannot move out of position when the carriage has been placed in the operating position on the mast.

In operation, the carriage is caused to traverse the mast through actuation by the hydraulic cylinder assembly and carries the load on the fork 20 as required by the use of the vehicle. The rollers 24 travel vertically in the channel 14 and roll on the inner walls of the flange sections on the channel 14 as required by the load and forces applied to the carriage 18. The upper rollers 24 roll on the forward flange while the lower rollers 24 operate on the rearward flange of the channel 14. Cantilever bending of the pin for support of the roller is eliminated by the yoke 26 which carries the outer end of the pin 28. By this arrangement, the roller will roll straight and true, the axis of rotation being always parallel to the surface on which the roller runs. The rollers, therefore, guide the carriage in a fore and aft direction and provide a friction free means of restraining the carriage to a predetermined path of travel.

When loads applied to the carriage are off center, the carriage has a tendency to move toward one side of the mast. This results in the carriage structure bearing against the mast which must be overcome by suitable means such as the flattened head 34 of the pin 28. The broad surface of the head 34 carries the side load which results from the eccentric load on the carriage as the carriage moves vertically in the mast. To obtain the proper distance between the outer faces of the heads 34 on the opposite sides of the carriage, shims 36 may be added between the heads 34 and the yokes 26 to obtain the dimension required to eliminate unnecessary looseness and play. The use of the flat head 34 overcomes the difficulties attendant with the operation of rollers for carrying the side loading.

It is to be understood that the specific nature of the present disclosure is not intended to be restrictive or confining and that various rearrangements of parts and modifications of design may be resorted to without departing from the scope or spirit of the invention as herein claimed.

What is claimed is:

1. In a lift truck having a mast with opposed vertical channel members opening toward each other, a carriage for vertical reciprocation on said mast, a guide member on the carriage, and guide means on the guide member for engagement with the channel, said means comprising a pin projecting from the guide member, a yoke affixed to the guide member and carrying the free end of said pin, and a roller on said pin intermediate the yoke and the guide member for positioning the carriage relative to the mast as the carriage moves along its path of travel.

2. In a lift truck having a mast with opposed vertical channel members opening toward each other, a carriage for vertical reciprocation on said members, guide means on the carriage for engagement with the channel members, said means comprising a pin projecting from the carriage, a yoke affixed to the carriage and carrying the free end of said pin, and a roller on said pin intermediate the yoke and the carriage for movement along the channel member whereby the carriage is positioned relative to the channel members as the carriage moves along its path of travel.

3. In a mast and carriage structure for a lift truck having opposed vertical channel members opening toward each other, a carriage for vertical reciprocation on said channel members, guide means on the carriage for engagement with the channel, said means comprising a pin projecting from the carriage, a yoke affixed to the guide member and carrying the free end of said pin, and a roller on said pin intermediate the yoke and the guide member for positioning the carriage relative to the channel members as the carriage moves along its path of travel.

4. In a mast and carriage structure for a lift truck, guide means for shiftably carrying the carriage along the mast comprising a pin projecting from the carriage, a yoke affixed to the carriage and carrying the free end of said pin, a roller on said pin engageable with the mast, and a head on the pin for sliding engagement with the mast for positioning the carriage laterally relative to the mast.

5. In a mast and carriage structure for a lift truck, guide means for shiftably carrying the carriage along the mast comprising a pin projecting from the carriage, a yoke affixed to the carriage and carrying the free end of said pin, a roller on said pin engageable with the mast, and a flat elongated head on the pin for sliding engagement with the mast whereby the carriage is positioned laterally relative to the mast.

6. In a mast and carriage structure for a lift truck, guide means for shiftably carrying the carriage along the mast comprising a pin projecting from the carriage, a yoke affixed to the carriage and carrying the free end of said pin, a roller on said pin engageable with the mast, a head on the pin for sliding engagement with the mast for positioning the carriage laterally relative to the mast, and a shoulder on the yoke adjacent the head of the pin for preventing rotation of the pin as the roller rotates relative to the carriage.

JOSEPH A. FRISCHMANN.
